CARRYING CASE FOR BOTTLES

Kenneth K. Hudson, Tampa, Fla.

Application January 2, 1953, Serial No. 22,996

Term of patent 14 years

(Cl. D58—5)

To all whom it may concern:

Be it known that I, Kenneth K. Hudson, a citizen of the United States, residing at Tampa, State of Florida, have invented a new, original, and ornamental Design for a Carrying Case for Bottles, of which the following is a specification, reference being had to the accompanying drawing, forming a part hereof.

Fig. 1 is a top plan view of a carrying case for bottles, showing my new design.

Fig. 2 is a side elevation thereof.

Fig. 3 is a bottom view thereof.

Fig. 4 is an end elevation thereof.

Figs. 5, 6 and 7 are a side elevation view, a bottom plan view and an elevation view, respectively, of the longitudinal separator portion thereof removed from the case.

Fig. 8 is a top plan view of the case with the separator portion removed therefrom, one end of the case being broken away; and

Figs. 9 and 10 are cross-section views of the case with the separator portion removed therefrom, one end of the case being broken away, and

taken on the lines 9—9 and 10—10, respectively of Fig. 8.

The separator, shown detached in Figs. 5 to 7, the finger slot and handle in Fig. 9, and the bottom studs in Figs. 8, 9 and 10, all are features of the appearance of the assembled case, visible to an observer looking down and from the side (as when the case is on the floor or on a counter), although concealed in Figs. 1 to 4 by reason of the projection used.

I claim:

The ornamental design for a carrying case for bottles, as shown.

KENNETH K. HUDSON.
